UNITED STATES PATENT OFFICE.

HENRY KIELBERG, OF MARTINS FERRY, OHIO, ASSIGNOR TO WHITAKER-GLESSNER COMPANY, OF WHEELING, WEST VIRGINIA, A CORPORATION OF WEST VIRGINIA.

BURNER FOR GAS HEATERS.

Application filed April 12, 1922. Serial No. 551,861.

To all whom it may concern:

Be it known that I, HENRY KIELBERG, a citizen of the United States of America, and resident of Martins Ferry, county of Belmont, and State of Ohio, have invented certain new and useful Improvements in Burners for Gas Heaters, of which the following is a specification.

This invention relates broadly to gas burners, and more specifically to burner grids for gas heaters.

The primary object of the invention is to provide an improved form of grid for gas burners of the character employed in association with the clay radiants of gas heating stoves.

A further object is to provide a grid of the character referred to having simple and improved means whereby it is mounted in place in a heater.

In describing the invention in detail, reference is herein had to the accompanying drawings, in which—

Figure 1 is a top plan view of a grid constructed in accordance with my invention, the same being shown mounted;

Figure 2 is a side elevation of the grid; and—

Figure 3 is an enlarged section on line 3—3, Fig. 1.

Referring to said drawings, 1 and 2 indicate upper and lower sheet-metal companion members constituting a burner support for gas heaters. Said members have therein registering apertures of circular form and have the edges encircling said openings flanged in opposite directions to provide therebetween a circular dove-tail channel 4 in which is received a correspondingly shaped rib or annulus 3 formed upon the lower portion of the body 5 of a one-piece cast-metal grid, whereby said grid is stationarily supported.

Provided in the upper face of said grid body 5 is a central basin-like cavity 6 of considerable depth, and leading radially inward through the upper cavity-encircling edge of said body and communicating at their inner ends with said cavity are numerous grooves or channels 7 separating upright equispaced spurs 8 having a circular

arrangement. Extending vertically through the grid body and having their upper ends opening outward through the spurs 8 are small bores 9 which constitute ports or passages through which gas is directed upward.

A circular wall of flame is created when the gas issuing from the ports or passages 9 is ignited. The radial channels 7 allow of an inrush of air to the central cavity 6 whence said air rises within the confines of said flame wall for mixing with the gas, thus effectively promoting combustion.

What is claimed is—

1. A grid for radiant heaters consisting of a circular metal body having a central cavity in its upper face and provided with a plurality of upright gas passages arranged in encircling relation to said cavity, the cavity-encircling upper face of said body having radial channels located intermediate said gas passages and communicating at their inner ends with said cavity, said channels constituting passages for air.

2. A grid for radiant heaters consisting of a circular metal body having a plurality of circularly-arranged gas passages opening upward therethrough adjacent to its outer edge and having a concavity in its upper face located inward of said passages, said body being also provided intermediate the various gas passages with radial air passages which open into said concavity.

3. A grid for radiant heaters consisting of a circular metal body having an annular seating rib, said body having a plurality of gas passages opening upward therethrough adjacent to its outer edge and having a concavity in its upper face located inward with respect to said passages, and radially extending channels formed in said upper face between the various passages, said channels opening into said concavity and constituting air passages.

4. In a gas heater, a burner support comprising a pair of superposed sheet metal members provided with registering openings, the opening-defining edges of said members being flanged in opposite directions to form a circular dove-tail channel, and a circular grid carried by said members, said grid consisting of a circular body having an annular

dove-tail rib seated in said channel, said body having a plurality of vertical gas passages extending therethrough adjacent to its outer edge and having a central concavity in its upper face, the portion of said face which encircles said concavity being separated by the provision of alternate radial channels and upright spurs, said gas passages opening upward through said spurs,

and said radial channels forming passages 10 for air.

In testimony whereof, I affix my signature in presence of two subscribing witnesses.

HENRY KIELBERG.
